US00D756513S

(12) **United States Design Patent**
Cheney

(10) **Patent No.:** **US D756,513 S**
(45) **Date of Patent:** **** May 17, 2016**

(54) **ORTHOPEDIC IMPLANT INSERTION
DEVICE**

(71) Applicant: **BioMedical Enterprises, Inc.**, San Antonio, TX (US)

(72) Inventor: **Daniel F. Cheney**, San Antonio, TX (US)

(73) Assignee: **BioMedical Enterprises, Inc.**, San Antonio, TX (US)

(**) Term: **14 Years**

(21) Appl. No.: **29/509,097**

(22) Filed: **Nov. 13, 2014**

(51) **LOC (10) Cl.** **24-02**

(52) **U.S. Cl.**

USPC **D24/133**

(57) **CLAIM**

The ornamental design for an orthopedic implant insertion device, as shown and described.

DESCRIPTION

FIG. 1 is a perspective view of the orthopedic implant insertion device;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof illustrating the orthopedic implant insertion device engaging an orthopedic implant retaining device and orthopedic implant.

The broken lines shown in FIGS. 1-8 represent portions of the orthopedic implant insertion device and an orthopedic implant retaining device and orthopedic implant that forms no part of the claimed design.
